MARINE DRILLING

Augustine J. Tucker, Houston, Tex.

Application May 4, 1946, Serial No. 667,290

5 Claims. (Cl. 255—2)

1

This invention relates to marine drilling and particularly to the drilling of oil wells under water.

Heretofore, so far as I am aware, all methods actually used or proposed for drilling in submerged lands require the establishment of a solid platform, either on piling or on submergible barges or caissons, upon which the conventional drilling derrick and drilling machinery may be mounted and drilling conducted therefrom in the usual manner.

Such methods have been successful and reasonably economical when confined to drilling in relatively shallow water areas. However, since the depth of the water puts a physically practical as well as an economically practical limit upon the driving of piles or the construction and operation of a suitably sized submergible barge, the practical maximum depth for these types of operation has been found to be of the order of perhaps 50 to 75 feet. Furthermore, unless reasonably well protected from excessive wind and wave conditions, drilling by these methods, even in shallow water, is attended by considerable difficulty and hazard.

Since various geological investigations have indicated the probable existence of oil and gas fields under the Continental shelves, particularly of the United States, which extend many miles out into the oceans under water depths of several hundred feet or more, the problem of drilling for oil under water of such depths, if solved, must be solved by an approach and methods which are quite different than those used heretofore in drilling through shallow water.

In conventional drilling, whether practiced on dry land or through shallow water, using the submerged barge or piling arrangements referred to, a relatively rigid connection must be maintained at all times between the well and the drilling equipment. The surface casing, for example, through which the drilling operations are conducted, forms such a connection. The drill stem, in the case of rotary drilling, is another part of such a connection. The result of this conventional arrangement is that substantially no relative lateral movement may be permitted between the well and the surface equipment. It is for this reason that conventional marine drilling techniques require a drilling platform which is rigidly anchored to, and supported by, the land underneath the water.

It seems obvious, therefore, that when the scene of drilling is shifted to the open ocean in areas where the water depths are of the order of sev-

2

eral hundred feet, not only is it practically unfeasible to construct supporting structures which will extend to the bottom at such depths, but also the problem of anchoring such a structure, with sufficient rigidity to withstand the heavy wave and wind conditions normally present in the open ocean, becomes well nigh insurmountable.

Moreover, even if it were possible by existing methods to establish fixed platforms in the open ocean and to drill wells there, such structures, if left in place after the well is completed, since they extend to the surface, would constitute serious hazards to ocean navigation which could be a matter of considerable concern to ship operators. If it were possible to remove the platform structure, the well head would remain so near the surface that it would likewise present an objectionable navigational hazard.

Accordingly, a principal object of this invention is to provide a method and apparatus for successfully drilling wells through deep water.

Generally speaking, the method of this invention for accomplishment of the aforesaid principal object contemplates employment of a floating platform on the water surface for supporting the drilling equipment, a well head, through which the drilling operations are conducted, but which is submerged at a substantial depth below the water surface, and generally flexible drilling and other operating connections between the floating platform and the submerged well head.

The floating platform may be any suitable form of ship or vessel on which the drilling equipment is mounted. The submerged well head is of a novel form which includes a working platform adapted to be attached to the top of the well casing but at sufficient depth below the water surface, so as not to constitute a navigational hazard and to be unaffected by surface wind and wave action. The flexible drilling connections between the vessel and the well head comprise an engine-in-head bit driven by hydraulic fluid supplied from the surface vessel through flexible drill pipe stored and fed from the vessel, and a flexible fluid return line, enclosing the flexible drill tube and connecting the well head with the vessel.

With apparatus such as is generally described above, a substantial degree of movement of the surface equipment relative to the well head can occur without hazard to the drilling operation and wells can be drilled thereby in open ocean areas through substantial water depths.

Other objects and advantages of this invention will be readily apparent from the following detailed description when read in conjunction with the accompanying drawings which illustrate useful embodiments in accordance with this invention.

In the drawings:

Fig. 1 is a plan view of the layout of the mooring connections for the operating vessel;

Fig. 2 is a side elevation showing the general arrangement of the well head, surface vessel and mooring connections in relation to the water surface and underlying land;

Fig. 3 illustrates the general assembly of the surface vessel, well head, well and drilling equipment, in accordance with this invention; and

Fig. 4 is a vertical, largely sectional view of the well head which shows the significant details thereof.

Referring to the drawings, Figs. 1 and 2 in particular, a number of heavy mooring buoys 10, arranged in a circle on the water surface, are anchored to the land bottom by means of anchors 11, preferably of the mushroom type, being connected thereto by chains 12, the lengths of which are preferably about 50% greater than the depth of the water in which the buoys are moored. The number of buoys may be varied, six being shown by way of example. Similarly the diameter of the circle on which the buoys are moored may be varied and is largely dependent upon various conditions to be faced, such as the depth of the water, the size of the vessel employed in the drilling operations, and wind and wave conditions generally prevalent in the areas where drilling is to be conducted. An operating vessel 13, with its bow generally centered in the mooring circle, is suitably moored fore and aft to the circle of buoys by means of cables 14, in such a manner as to reduce to a minimum the degree of yaw, particularly, and to thereby hold the bow of the vessel as nearly centrally positioned within the circle of buoys as possible. It will be obvious that the other motions commonly affecting a vessel in the open sea will not be materially altered or affected by the type of mooring, since it will be clear that pitching, rolling, and vertical rise and fall of the vessel will be very little affected by the mooring described. While it would be desirable if all such motions could be eliminated or greatly reduced, this is deemed to be practically impossible of accomplishment and is not an impediment to achieving the objects of this invention.

Referring particularly to Fig. 2, where the underwater mooring connections are best illustrated, a well head, designated generally by the numeral 15, is moored in the center of the circle formed by buoys 10 and submerged a suitable depth below the surface. Cables 16 connect the well head to buoys 10 and to anchor chains 12. Arrangement is made, when drilling of the well is completed, to release each of the combined connections formed by cables 16 and chain 12 from their attachment to the buoys 10, so that these combinations will form direct moorings from anchors 11 to the well head, the general position of this connection being shown at 16'. When thus moored to the buoys 10, well head 15 will be generally aligned with the bow of vessel 13 from which drilling operations are conducted, as will be described hereinafter. Although the vessel will necessarily undergo various degrees of motion, under the action of wind and wave, while the well head will be relatively unaffected, the moor-

ing arrangement described will keep the lateral movements of the bow of vessel 13 relative to the well head at a minimum.

Well head 15 (Fig. 4) comprises upper and lower flotation chambers 17 and 18 respectively, which are vertically spaced apart and rigidly connected together by means of cross braces 19. These flotation chambers 17 and 18 are equipped with conventional control gear (not shown) for filling and emptying the chambers in order to control the buoyancy and thereby the depth of submergence of the well head. The arrangement of the flotation chambers is so designed, that operation of the control gear will cause the well head to float in an upright position while submerged at any desired suitable depth. Mooring lugs 19a are attached to upper flotation compartment 17 for connection thereto of mooring cables 16.

Upper flotation chamber 17 is provided in the top thereof with a large funnel-shaped mouth 20 which connects to a large diameter tube 21 extending entirely through the center of both upper and lower flotation chambers. A section of tube 21 between the two chambers may be cut out to provide access to the interior of the tube and to the equipment passing therethrough. For convenience, tube 21 may be composed of two axially aligned spaced apart sections as illustrated particularly in Fig. 4. The top of chamber 18 is provided with an enclosing railing 22 and serves as a working platform for divers in conducting certain operations to be described. The upper end of the section of tube 21 passing through lower chamber 18 is provided with any suitable form of slip bowl 23 for the reception of pipe gripping slips 24. The upper section of tube 21 passing through upper chamber 17 is equipped with vertically spaced sets of spring controlled centering pawls 25 which are employed to center and to guide pipe, such as casing 26, which is passed through the tube. A similar set of centering pawls 27 are disposed near the lower end of the lower section of tube 21 passing through lower chamber 18. Slips 24 and slip bowl 23 cooperates with pawls 27 for centering the pipe sections passing through the lower section of tube 21 and for aligning them with the pipe sections passing through the upper section of tube 21.

The lower end of tube 21, which extends below chamber 18, is provided with a collar 28 adapted for attachment thereto of a pilot tube 29 which is of a length sufficient to extend well into the land bottom from the lower end of the well head. Pilot tube 29 acts as a stabilizing anchor for the well head as well as a guide casing through which all drilling operations are conducted.

The above described equipment is assembled and arranged in preparation for the drilling operations, proper, in the following manner: The mooring buoys 10 are anchored, as described above, in a circle. The diameter of which may be, for example, 1200 feet. The well head is then towed into the center of the mooring circle, and with cables 16 attaching it to the buoys, the controls on the flotation chambers are operated to cause the well head to attain an upright position, while being submerged to the desired depth. This depth is preferably on the order of about 100 feet, as this is a depth which is sufficiently shallow so that divers may work reasonably comfortably on the well head and which is at the same time, well below a depth at which the well head will be affected by surface wind and wave conditions and out of the way of any

ordinary surface traffic. When the well head has attained the desired submerged position, in the center of the mooring circle, vessel 13 is then moored to buoys 10 so that its bow is substantially centered in the mooring circle and therefore, in general vertical alignment with the well head. As indicated above, exactitude of alignment is unnecessary, it being one of the advantages of this invention that such exact alignment need not be maintained.

With the vessel and well head in position as noted above, sections of pilot tube 29 are lowered from the vessel through mouth 20 of the well head and as the sections pass downwardly through tube 21, they are made up by divers working on the well head until the pilot tube attains a length sufficient to reach from the bottom of the well head to the underlying land bottom. Enough additional sections are added to the pilot tube to allow its lower end to sink as far as it is capable, by its own weight, into the ocean bottom. When this point is attained, the upper end of pilot tube 29 is welded to collar 28 and the well head is thus provided with a solid connection to the ocean bottom and which cooperates with the moorings to buoys 10 to hold the well head firmly in place for the conduct therethrough of the subsequent operations.

With the well head in position and stabilized, as described, drilling operations may be begun and such operations and the equipment employed therefor will now be described.

A hollow buoy 30, termed the "drilling buoy," is moored to the bow of vessel 13 above the well head. Buoy 30 is shown in Fig. 3 outside the bow of the vessel, chiefly for purposes of clearer illustration. In practice this buoy will normally be positioned inside a well within the bow of the vessel, as indicated in Figs. 1 and 2, where it will be better protected against wave and wind conditions and more accessible to the operating crew on board the vessel.

The drilling string comprises a drill bit 31, of generally conventional construction, which is attached to any suitable form of in-head engine 32, which may be of turbine, rotary or reciprocating type, above which is connected a stabilizing cylinder 33 of suitable length, for example, 50 feet, to guide the bit in the drilling of a straight hole. Drill bit 31, engine 32, and stabilizing cylinder 33 comprise what may be termed the "drilling head." Connected to the in-head engine 32, through stabilizing cylinder 33, is a flexible drill pipe 34 which extends upwardly through pilot casing 29, well head 15 and drilling buoy 30 onto the deck or into the hold of vessel 13, where it is coiled down and connected to a slush pump 35. This flexible drill pipe may be of any form suitable for the purposes of this invention, and may conveniently be of the same general type as was employed, for example, in the flexible pipe lines laid through the English Channel during the war, being adapted to withstand a bursting pressure of over 4000 pounds per square inch. Flexible drill pipe 34 is fed and guided over the bow of the vessel by means of a series of sheaves and rollers, designated generally as a reeling mechanism 36. A cable 37 fed from a winch 38, is strung over conventional deck booms 39 and parallels the drill pipe, being connected to stabilizing cylinder 33 of the drilling head. Cable 37 is employed in connection, particularly with the raising of the drill pipe, as will be described hereinafter. A drilling mud tank 40, is provided within the hull of vessel 13

and is divided by a partition 41 to form a suction compartment 42 from which pump 35 takes suction on the drilling fluid through a suction pipe 43.

- 5 Initial drilling operations for the purpose of setting surface casing are begun by lowering the drilling head through drilling buoy 30, well head 15 and pilot tube 29 to the bottom of the pilot tube. Drilling is begun, the drilling fluid, after 10 driving bit 31, being discharged into the annular space between the wall of the well and the exterior of the drill pipe. During this initial operation the discharged drilling fluid and drill cuttings are washed upward to the mouth of the 15 well head which is open to the surrounding water, the fluid and cuttings being merely dissipated therein. When the well has reached a suitable depth for the purpose of setting surface casing, an air supply 50 on board vessel 13 is 20 connected to the inbound end of flexible drill pipe 34 and is employed to blow the pipe clear of the drilling fluid. As the heavy drilling fluid is blown from the drill pipe and is replaced by air the drill pipe becomes increasingly buoyant, 25 and may be very easily withdrawn from the well merely by reversing reeling mechanism 36, the drill pipe being coiled down as it comes aboard. Cable 37 may be employed to assist this operation, if required. However, as a result of the 30 buoyancy thus imparted to the drill pipe, the effective weight applied to the cable or to the reeling mechanism is relatively small, and the need for the very heavy derricks and hoisting equipment normally required in rotary drilling 35 is thereby avoided. In fact, cable 37 will serve ordinarily for applying an emergency pull to the drill string, in the event the drill head should stick in the hole. By providing suitable valving (not shown) in the drill head, the lower end of 40 the drill pipe may be closed off, when the air has finally displaced all the drilling fluid, such valving being of a generally conventional form which is responsive to the change from liquid to gas passing therethrough to effect closing of 45 the valve. With the drill pipe filled with air, it will, of course, have great buoyancy, so that, as indicated, minimum effort is required to remove it from the well. In fact, control must be exercised in the rate of displacement of drilling 50 fluid by air, in order that the rate of withdrawal of the drill pipe at all times will be under sufficient control to permit a steady and smooth operation of the reeling mechanism in coiling down the drill pipe as it comes aboard.
- 55 When the drill string has been withdrawn, as described, following the drilling of sufficient hole for setting the surface casing, the latter, designated by numeral 26, is lowered in sections from vessel 13, through the well head, the joints being 60 made up by divers working on the well head platform, and the string of casing, thus made up, is lowered through pilot tube 29 into the well and set on the bottom thereof. The last section of casing 26 is allowed to extend above the top of the well head and a master drilling gate valve 46 and a blow out preventer 47, all of generally conventional construction, are connected to the top of casing 26. A section of large diameter flexible tube 48, which is not required to withstand high 65 pressures, and may, therefore, be of any suitable low pressure construction, is lowered through drilling buoy 30 and its lower end connected to blow out preventer 47. The upper end of flexible tube 48 is provided with a T fitting 49, the 70 center branch of which has a flexible hose 51 con- 75

nected thereto, and discharges into mud tank 40. The other end branch of T fitting 49 is provided with a stuffing box 52 through which drill pipe 34 and cable 37 are adapted to pass for further drilling operations. Suitable hydraulic connections 53, operated from drilling buoy 30, are connected to the operating handles of drilling master valve 46 and blow out preventer 47 to enable controlling these devices from the drilling buoy in the event it is necessary to close these devices off. 10

Flexible tube 48, connected as described, forms a continuous, closed, flexible connection between the surface of the water and the well head, represented by the upper end of casing 26, and this flexible connection is utilized for all further drilling operations. Surface casing 26 may now be cemented in the conventional manner, through flexible tube 48 and upon completion of this operation, drilling of the well proper is commenced by feeding the drill pipe through flexible tube 48 and casing 26 to the bottom, and pumping drilling fluid from tank 42 to the drill head to drive the bit. The drilling fluid exhausting from the drilling head will now flow back to mud tank 40, being confined in the annular space between the drill pipe and casing 26, and then between the drill pipe and flexible tube 48, and the conventional drilling mud circulation will thus be maintained. 25

When drilling is completed to the producing formation, the final casing and tubing strings may be run into the well directly from the surface, if the weather is sufficiently calm, or may be lowered in sections, being made up by divers working at the casing head. The usual well head flow connections are then made to the top of the casing, 30 and the well drilled in and placed in production in the usual manner.

To avoid bringing any final well connections to or near the surface of the water, the usual production outlets at the well head (not shown) may be connected by a submarine pipe line to a suitable shore station where the usual oil and gas separators and storage tanks may be located. 40

When the well is completed and placed in production, cables 16 and anchor chains 12 may be released from buoys 10 and the anchors connected directly to the well head by cables 16', as noted above. The mooring buoys 10 may then be removed, and upon removing vessel 43 from the well vicinity, together with drilling buoy 30, all possible navigational hazards will be removed. A small marking buoy may be left to mark the location of the well, or conventional detection gear for detecting underwater objects may be employed to locate the well, whenever it may be desired to return to it. 50

Many alterations and changes may be made in the details of the apparatus and methods herein described without departing from the scope of the appended claims but within the spirit of this invention. 60

What I claim and desire to secure by Letters Patent is:

1. Marine drilling apparatus, comprising in combination, a floating vessel moored on the surface of a body of water, a chambered structure of controllable buoyancy submerged beneath the vessel and between the surface and the underlying land bottom, a rigid conduit connecting said structure to said bottom, a large diameter tube composed of two axially aligned spaced apart sections extending through said structure and communicating with said conduit, a submerged working platform disposed on said structure, an opening in said tube adjacent said platform to

provide access to the interior of said tube, a submerged well casing extending through said tube and said conduit, a flexible drilling-through conduit extending between the upper end of said casing and said vessel, and means for feeding a flexible drill stem from said vessel through said flexible drilling-through conduit. 10

2. Marine drilling apparatus, comprising in combination, a vessel afloat on a body of water, a plurality of mooring buoys arranged generally circularly about said vessel and anchored to the underlying land bottom, mooring connections between said vessel and said buoys, a buoyant working platform submerged in said body of water below said vessel and above the underlying land bottom, mooring connections extending from said platform to said buoys and thence to said anchors, said mooring connections being releasable from said buoys, a large diameter tube composed of two axially aligned spaced apart sections extending through said platform, an enlarged conduit connected to said tube and extending to said land bottom, a submerged well casing extending through said tube and said conduit, and a flexible drilling-through connection extending between said vessel and said casing. 15

3. Marine drilling apparatus, comprising in combination, a floating vessel moored on the surface of a body of water, a buoyant working platform submerged in said body of water below said vessel and above the underlying land bottom, a large diameter tube composed of two axially aligned spaced apart sections extending through said platform, an enlarged rigid conduit connected to one end of said tube and extending to the land bottom, a submerged well casing extending through said tube and said conduit, and a flexible drilling-through conduit extending between the upper end of said casing and said vessel. 20

4. Marine drilling apparatus, comprising in combination, a floating vessel moored on the surface of a body of water, an underwater working platform submerged in said body of water between said vessel and the underlying land bottom, a conduit forming a rigid connection between said platform and said bottom, a large diameter tube composed of two axially aligned spaced apart sections extending through said platform communicating with said conduit, a well casing extending through said tube and said conduit into said bottom, well control fittings mounted on the upper end of said casing, a flexible drilling-through conduit connected to said control fittings and extending to said vessel, and means on said vessel for feeding and actuating a flexible drill stem with a drill bit mounted thereon through said flexible connection and said casing for drilling a well. 25

5. Marine drilling apparatus, comprising in combination, a floating vessel moored on the surface of water, a buoyant working platform submerged in said body of water below said vessel and above the underlying land bottom, a large diameter tube composed of two axially aligned spaced apart sections extending through said platform, an enlarged rigid conduit connected to one end of said tube and extending to said land bottom, a submerged well casing extending through said platform and said conduit into said bottom, a flexible drilling-through conduit connecting the upper end of said casing to said vessel, a flexible hollow drill stem extending from said vessel through said flexible conduit and said casing to said bottom, a fluid actuated engine-in-head drilling bit connected to the lower end of said drill stem, and means on said vessel to sup-

ply actuating fluid through said hollow drill stem to said bit.
